TIMEPIECE CALIBRATION RECORDING APPARATUS

Walter J. Loria and Jerome Suhre,
New York, N. Y.

Application September 13, 1945, Serial No. 615,958

9 Claims. (Cl. 73—6)

1

The present invention relates to timepiece calibration recording apparatus and more particularly to such apparatus of the all-electronic type which is substantially inertialess for recording the accuracy of a watch or clock in order to observe its rate of gain or loss of time.

In the repair or adjustment of a watch or clock and also in routine tests it is essential to speedily determine the accuracy thereof. It is also important to know the characteristics of the beat of a watch or clock so that irregular beats may be detected.

Heretofore, it has been usual for the horologist to utilize the old time worn method of observing its rate over a long period of time as compared with a standard chronometer. Other methods have been developed, as for example, the utilization of the stroboscopic principle as applied to visual indicators. Recording instruments have been used with electronic stylus control and embodying rotating drums and stylus action based on the principle of inked ribbon and reciprocating stylus action producing response in the form of a series of dots corresponding to the beat of the watch.

These instruments are incapable of responding to rapid beat movements and give no qualitative analysis either of the beat or of the sounds produced by the movement between the beats. The present invention contemplates the provision of a watch and clock time checking device that is sensitive to the beat of the most rapid watch and accurately checks and records the degree of regulation of the timepiece under examination, as well as the nature and characteristic of the beat, and the integrated sounds produced by the movement, to a degree not heretofore obtainable and the operation of which simplifies the known methods of watch and clock regulation.

The present invention also contemplates a means of recording the beat of a watch and the integrated sounds of a watch or clock mechanism so that qualitative analysis thereof may speedily and accurately be made, an accomplishment hitherto unknown to the art, thereby affording the horologist with a basis for quick and accurate diagnosis and adjustment.

More specifically, the present invention provides a recording device for recording the accuracy of a watch or clock and which determines the nature and characteristics of the beat to a degree not heretofore obtainable and with a sensitivity hitherto unknown and which is simple and automatic in operation.

2

Furthermore, the invention provides means for recording the duration of the beat of the watch and the integrated sounds thereof, an achievement which has heretofore been unknown in the horological art.

In accordance with the invention there is provided timepiece calibration recording apparatus comprising an electrical pickup effective to derive periodic electrical signals precisely related in frequency to the timing of a timepiece being calibrated, a standard source of periodic reference electrical signals, and a moving carriage adapted to receive a calibration chart movable therewith. The apparatus also includes a recording stylus movable across a chart on said carriage to scan the same and means responsive jointly to the derived signals and the reference signals for causing the stylus to make two groups of periodic traces on a chart on said carriage, each positioned in dependence upon the frequency of one of such signals, whereby the relative patterns of the traces are representative of the calibration of the timepiece.

For a better understanding of the present invention, together with other and further objects thereof, reference is had to the following description taken in connection with the accompanying drawings, and its scope will be pointed out in the appended claims.

The accompanying drawings referred to herein and constituting a part hereof illustrate an embodiment of the invention and together with the description serve to explain the principles of the invention.

Figures 1a and 1b are schematic wiring diagrams of electric elements used in the apparatus.

Figure 2 is a top elevation, partly in cross section, of one embodiment of the calibrating apparatus according to the present invention.

Figure 3 is a side elevation, partially in cross section, of the apparatus of Figure 2.

Figure 4 is a diagram of a pattern produced by the apparatus.

Referring now to Figures 2 and 3 of the drawings, the timepiece calibration recording apparatus embodying the invention and adapted to make a record on an electro-sensitive chart comprises a portable casing including a chassis portion 69 and a hood portion 9. Secured to the side wall 8 of hood 9 there is provided a mounting 3 so arranged that a timepiece such as a watch can be placed thereon with any orientation. Affixed to the mounting 3 is an electrical pickup effective to derive periodic elec-

trical signals precisely related in frequency to the timing of the timepiece being calibrated. This apparatus may comprise a microphone 4 of the crystal or contact type cushioned to absorb outside shocks and effective to develop signals representative of the sound beats of the timepiece in duration and frequency.

The recording apparatus also includes a moving carriage adapted to receive a calibration chart; specifically projecting through base 2 of chassis 60 is a shaft 5 of synchronous motor 6 which is affixed to the underside of base 2. Secured to the shaft 5 of synchronous motor 6 is an electrically conductive disc turntable 7 for receiving a circular chart 28 of electrosensitive type effective to produce a mark or trace varying in intensity and duration with the value of an electric current passed therethrough. The synchronous motor 6 is of a conventional type designed to rotate the turntable 7 at 60 R. P. M. when connected to the commercial 60 cycle alternating-current supply. The recording apparatus further includes a recording stylus movable across the chart 28 on the carriage or turntable 7 to scan the same. Specifically, the stylus 11 is reciprocable radially across the chart 28 to scan the same with a time-linear trace movement and a rapid retrace movement. The mechanism for imparting this motion to the stylus 11 comprises a shaft 10 projecting through the wall 8 of hood 9 and connected at one end with stylus 11, which is a metal ballpointed needle and so affixed that outward movement of shaft 10 will project stylus 11 radially across and toward the center of turntable 7. Shaft 10 is arranged within housing 9 to be guided accurately in its movement toward the center point of turntable 7 by guide bars 12 which guide a cross piece 14 to which shaft 10 is affixed. The shaft 10 and stylus 11 are actuated by cam 15 revolved by a motor 16, affixed to the top of chassis 60. Guide bars 12 are secured to end plates 17 and 18 which are affixed and secured to the base 2 of chassis 60. Shaft 10 has connected or affixed to its end opposite the stylus a roller 39 which rides on cam 15. The driving mechanism for moving the carriage or turntable 7, specifically the synchronous motor 6, operates at a speed which is very high relative to that of the driving mechanism for the stylus 11, that is, the synchronous motor 16. For example, the motor 6 may drive the turntable 7 at 60 R. P. M. while the motor 16 drives the cam 15 at 1 R. P. M.

Enclosed within housing 9 and affixed to the base 2 of chassis 60 is amplifier unit 19, a conventional high-gain electronic amplifier designed to produce a power output of 5 watts from the beat of the watch under test. Specifically, the amplifier unit 19 includes a conventional pentode amplifier tube 60a having its grid-cathode circuit connected to the microphone pickup 4 and provided with a grid-leak resistor 61 and a conventional cathode bias circuit 62. The anode circuit of amplifier 60a is provided with a load resistor 63 coupled by way of a capacitor 64 to the grid-cathode circuit of a second pentode amplifier tube 52, the anode circuit of which is coupled by way of a load resistor 64 and a coupling condenser 65 to the grid-cathode circuit of a power amplifier tube 56. The tubes 52 and 60a are provided with grid-leak resistors 67 and 68, respectively, and cathode biasing circuits 69 and 70, respectively. The anode circuit of amplifier tube 66 is coupled by way of a transformer 71 to the conductive stylus 11 by suitable flexible or

sliding contact connection (Figure 1a) to allow for its reciprocation. The recording apparatus includes also a standard source of periodic reference signals having a frequency of a value commensurable with the normal frequency of the sound beats of the timepiece. This reference signal source includes, enclosed within housing 9 and affixed to a side wall thereof, a tuning fork unit 40, consisting of tuning fork 41, made of magnetic material, an actuating electromagnet 43 wound on a soft iron core 45 mounted at right angles to one of the tines 53 of tuning fork 41. Also at right angles to the opposite tine 54 of tuning fork 41 is a pickup winding 42 which contains a permanent magnet core 44. Tuning fork unit 40 also includes a feedback amplifier comprising a triode vacuum tube 47 having its grid-cathode circuit connected to the pickup winding 42 and its anode circuit coupled by way of load resistor 72 and coupling condenser 57 to the grid-cathode circuit of a second triode vacuum tube 46, the anode circuit of which is connected to excite the actuating electromagnet 43 through a load resistor 43a. The tubes 46 and 47 are provided with cathode bias circuits 56 and 55, respectively, while tube 46 is provided with a grid-leak resistor 73.

The recording apparatus of the invention also includes a power supply circuit which may be conventional in construction, comprising an input transformer 23 having a primary winding 23a connected to supply circuit terminals 74, 74 through either a push button switch 20 or the contacts 22a of a relay 22, the winding of which is connected across the terminals 74, 74 through the normally closed contacts of a limit switch 24 actuated by the cross bar 14 of the stylus reciprocating mechanism. The transformer 23 is provided with a low-voltage secondary winding 23b for energizing the cathode heaters of the several amplifier tubes of the system; with a secondary winding 23c for energizing the filament of a double-anode rectifier tube 26; and with a mid-tapped secondary winding 23d providing with tube 26 a full-wave rectifying circuit. The filament of tube 26 is connected, through a conventional filter circuit 75, to the terminal +B, which is the positive terminal of the power supply output circuit. One of the chokes of the filter unit 75 comprises the winding of a relay 25 having contacts 27, 27a connected to complete the circuits of the motors 16 and 6, respectively.

Tuning fork unit 40 is a precision oscillator circuit whose frequency is mechanically determined by the fundamental frequency of the tuning fork 41 in a conventional manner. Briefly, vibration of tine 54 at the natural frequency of fork 41 induces a periodic voltage of the same frequency in pickup winding 42. This voltage is amplified in tubes 47 and 46 and fed back to actuating winding 43. This regenerative action maintains the tuning fork 41 in oscillation at its natural frequency in a conventional manner well understood in the art, and develops across load resistor 43a a periodic voltage constituting the source of reference signals of the apparatus. As stated above, the natural frequency of the tuning fork 41 should be commensurable with the normal frequency of the timepiece to be calibrated, that is, the ratio of these two frequencies should be a perfect number. For example, for a watch beating at the rate of 5 per second, the tuning fork 41 may have a natural frequency of 60 cycles per second, thus developing 12 oscillations per watch beat.

The recording apparatus also includes repeater means for clipping the reference signals to develop a periodic short-duration pulse wave and means responsive jointly to the signals derived from the watch beat and the reference signals for causing the stylus 11 to make two groups of periodic traces on a chart 28 on the turntable 7, each positioned in dependence upon the frequency of one of such signals. To this end, the voltage across resistor 43a is fed to vacuum tube 48 included in amplifier unit 19 through a coupling capacitor 76. Tube 48 is connected as a conventional resistance coupled amplifier but biased almost to "cut-off." The effect of this excessive bias, provided by cathode bias resistor 50 bypassed by capacitor 77, is to cause rectification and clipping of the output of tuning fork unit 40, producing a unilateral pulsating wave comprising short-duration pulses consisting of only the peaks of the tuning fork oscillations. The output of amplifier tube 48 developed across resistor 78 is fed through coupling capacitor 51 to the screen grid of vacuum tube 52 in amplifier 19. Thus, both the signals derived from the watch beats and the reference signals are amplified in tubes 52 and 66 and passed through transformer 71 to stylus 11. Therefore, amplifier 19 comprises means for impressing the signals derived from the watch beats and the clipped reference signals on the stylus 11 simultaneously.

In the use of the calibrating apparatus of the invention to ascertain the accuracy of the watch or clock under test, the timepiece is placed on mounting 3 in direct contact with microphone 4. Push button 20 is momentarily depressed, thus energizing the primary winding of transformer 23 and of relay 22, causing relay 22 to close its contacts 22a, thus maintaining flow of current to the primary winding of transformer 23 after removal of pressure on button 20. The energizing current passing through the relay 23 likewise passes through the contact points of limit switch 24. The secondary winding 23d of transformer 23 is connected to relay 25 through the rectifier 26 and, upon the heating of the cathodes of the tubes of the amplifier 19, relay 25 will be energized by the resulting flow of anode current, thus closing contacts 27, 27a of relay 25 and causing motors 6 and 16 to operate. Motors 6 and 16 are synchronous motors which have previously been described as operating at speeds of 60 R. P. M. and 1 R. P. M., respectively, from commercial alternating-current supply sources. The rotation of motor 6 in turn rotates turntable 7 through shaft 5. An appropriately sized disc-shaped chart of electrically sensitive paper 28, previously described, is placed on turntable 7 and secured in place and is rotated by the turntable 7 at a rate of 60 R. P. M. Stylus 11 is brought automatically into contact with the paper placed on the turntable 7 and, as the turntable 7 rotates progressively, moves radially toward the center of the disc, at the same time producing on the surface of the paper black markings corresponding in intensity and duration to the beat of the timepiece under test and to the frequency of the tuning fork 41. The stylus 11 is driven by shaft 10, guided, as already stated, by bars 12 and actuated by cam 15 driven by motor 16. When cam 15 completes one-half of a revolution, stylus 11 will have reached its terminal point on its approach to the center of turntable 7 and the test run will have been completed. The amplified and clipped reference signals from tuning fork unit 40 impressed on stylus 11 produce a series of

radial traces 28a each comprising a series of dots representative of the short-duration beats of the tuning fork oscillations. Simultaneously, the amplified signals derived from the watch beats by the microphone 4 produce a series of approximately radial traces 28b comprising a series of arcuate dashes representative of the watch beats in duration and time. The watch beats themselves are in the form of pulses of damped transient oscillations, the duration of which indicates to a horologist the nature of the escapement action.

The radial traces 28a corresponding to the frequency of the tuning fork are reference lines and if, for example, a 60 cycle fork is used there will be 60 radial lines equally angularly spaced around the chart 28 whose accuracy will be equal to the standard provided by the tuning fork. Against these traces will be read the record of the rate of gain or loss of the watch under test. If, for example, the watch under test produces a trace which cuts across a space separating two adjacent radial reference traces produced by the fork, there will be a gain or loss depending upon the direction of the curve of the watch trace, which can easily be seen.

The rate of gain or loss may be mathematically determined since, in the instrument described, the turntable 7 rotates at 60 R. P. M. or one revolution per second while the tuning fork 41 has a frequency of 60 cycles per second so that the space between adjacent radial reference traces is equal to one-sixtieth of a second. A gain of one radial line or one-sixtieth of a second in the run which is timed for one-half minute by one-half revolution of cam 15 shows that the time-piece is gaining one-thirtieth of a second in a minute or two seconds per hour or 48 seconds per day. Since there is considerable space between each reference trace, extremely small variations in time can be readily detected. It will be observed that cutting of the reference traces by the watch traces in a counterclockwise direction indicates a fast-running movement.

The regularity of the beat of the watch under test can quickly be determined by counting the reference traces between the traces produced by the tick of the watch. Equal spacing between traces on a five or six beat watch indicates a regular beat. Uneven spacing indicates an irregular beat.

It is also to be observed that this invention provides a means for instantly determining the number of beats per second produced by the watch, a feature new and unique. The apparatus is also capable of calibrating watches of any beat rate.

Markings appearing between the regular radial watch traces indicate sounds produced by an improperly operating watch which a horologist can interpret. Further, the trace-developing means are inertialess electronic circuit elements and apparatus so that sounds of a duration as brief as $1/1000$ of a second may be recorded. A qualitative analysis of the beat may be made by an observation of the track of light and dark markings within the beat marks which will be of prime importance to the horologist as indicating the condition of the timepiece under test.

While we have described in detail a modification of the present invention illustrated as embodied in a watch rate checking instrument, it is to be understood that changes may occur to those skilled in this art.

The invention in its broader aspects is not limited to the specific mechanism shown and described but departures may be made therefrom within the scope of the accompanying claims without departing from the principles of the invention and without sacrificing its chief advantages.

What is claimed is:

1. Timepiece calibration recording apparatus comprising: an electrical pickup effective to derive periodic electrical signals precisely related in frequency to the timing of a timepiece being calibrated; a standard source of periodic reference electrical signals; a moving carriage adapted to receive a calibration chart movable therewith; a recording stylus movable across a chart on said carriage to scan the same; and means responsive jointly to said derived signals and said reference signals for causing said stylus to make two groups of periodic traces on a chart on said carriage, each positioned in dependence upon the frequency of one of said signals, whereby the relative patterns of said traces are representative of the calibration of said timepiece.

2. Timepiece calibration recording apparatus comprising: an electrical microphone effective to derive periodic electrical signals representative of the sound beats of a timepiece being calibrated in duration and frequency; a standard source of periodic reference electrical signals; a moving carriage adapted to receive a calibration chart movable therewith; a recording stylus movable across a chart on said carriage to scan the same; and means responsive jointly to said derived signals and said reference signals for causing said stylus to make two groups of periodic traces on a chart on said carriage, each positioned in dependence upon the frequency of one of said signals, whereby the relative patterns of said traces are representative of the calibration of said timepiece.

3. Timepiece calibration recording apparatus comprising: an electrical pickup effective to derive periodic electrical signals precisely related in frequency to the timing of a timepiece being calibrated; a standard source of periodic reference electrical signals having a frequency of a value commensurable with the normal frequency of the sound beats of said timepiece; a moving carriage adapted to receive a calibration chart movable therewith; a recording stylus movable across a chart on said carriage to scan the same; and means responsive jointly to said derived signals and said reference signals for causing said stylus to make two groups of periodic traces on a chart on said carriage, each positioned in dependence upon the frequency of one of said signals, whereby the relative patterns of said traces are representative of the calibration of said timepiece.

4. Timepiece calibration recording apparatus comprising: an electrical pickup effective to derive periodic electrical signals precisely related in frequency to the timing of a timepiece being calibrated; a standard source of periodic reference electrical signals; a turntable adapted to receive a circular calibration chart; a recording stylus movable radially across a chart on said carriage to scan the same; and means responsive jointly to said derived signals and said reference signals for causing said stylus to make two groups of radial periodic traces on a chart on said carriage, each positioned in dependence upon the frequency of one of said signals, where-

by the relative patterns of said traces are representative of the calibration of said timepiece.

5. Timepiece calibration recording apparatus comprising: an electrical pickup effective to derive periodic electrical signals precisely related in frequency to the timing of a timepiece being calibrated; a standard source of periodic reference electrical signals; a moving carriage adapted to receive a calibration chart; a recording stylus reciprocable across a chart on said carriage to scan the same with time-linear trace movement and a rapid retrace movement; and means responsive jointly to said derived signals and said reference signals for causing said stylus to make two groups of periodic traces on a chart on said carriage, each positioned in dependence upon the frequency of one of said signals, whereby the relative patterns of said traces are representative of the calibration of said timepiece.

10 6. Timepiece calibration recording apparatus adapted to make a record on an electro-sensitive chart comprising: an electrical pickup effective to derive periodic electrical signals precisely related in frequency to the timing of a timepiece being calibrated; a standard source of periodic reference electrical signals; a moving carriage adapted to receive a calibration chart movable therewith; a recording stylus movable across a chart on said carriage to scan the same; and means for impressing both said signals on said stylus simultaneously for causing said stylus to make two groups of periodic traces on a chart on said carriage, each positioned in dependence upon the frequency of one of said signals, whereby the relative patterns of said traces are representative of the calibration of said timepiece.

25 7. Timepiece calibration recording apparatus comprising: an electrical pickup effective to derive periodic electrical signals precisely related in frequency to the timing of a timepiece being calibrated; a standard source of periodic reference electrical signals; a moving carriage adapted to receive a calibration chart movable therewith; a recording stylus movable across a chart on said carriage to scan the same; driving mechanism for moving said stylus; driving mechanism for moving said carriage at a speed which is high relative to that of said stylus; and means responsive jointly to said derived signals and said reference signals for causing said stylus to make two groups of periodic traces on a chart on said carriage, each positioned in dependence upon the frequency of one of said signals, whereby the relative patterns of said traces are representative of the calibration of said timepiece.

30 8. Timepiece calibration recording apparatus comprising: an electrical pickup effective to derive periodic electrical signals precisely related in frequency to the timing of a timepiece being calibrated; a standard source of periodic reference electrical signals; repeater means for clipping said reference signals to develop a periodic short-duration pulse wave; a moving carriage adapted to receive a calibration chart; a recording stylus movable across a chart on said carriage to scan the same; and means responsive jointly to said derived signals and said clipped reference signals for causing said stylus to make two groups of periodic traces on a chart on said carriage, each positioned in dependence upon the frequency of one of said signals, whereby the relative patterns of said traces are representative of the calibration of said timepiece.

35 9. Timepiece calibration recording apparatus adapted to make a record on an electro-sensitive

chart comprising: an electrical pickup effective to derive periodic electrical signals precisely related in frequency to the timing of a timepiece being calibrated; a standard source of periodic reference electrical signals; repeater means for clipping said reference signals to develop a periodic short-duration pulse wave; a moving carriage adapted to receive a calibration chart; a recording stylus movable across a chart on said carriage to scan the same; and means for impressing said derived signals and said clipped reference signals on said stylus simultaneously for causing said stylus to make on said chart one trace comprising a series of dots representative of said reference signals and a second trace comprising a series of dashes representative of said derived signals in timing and duration, whereby the relative patterns of said traces are representative of the calibration of said timepiece.
